AUTOMATIC HOOK

Application filed July 27, 1928. Serial No. 295,800.

This invention relates to an automatic hook, the hook, without the automatic feature, being of the kind extensively used in the handling of chilled cast iron car wheels.

5 The principal objects of the invention are to provide:

First. A simple and efficient device for automatically causing the engagement or release of the gripping jaws of a so-called hook 10 which is extensively used in the handling of chilled cast iron car wheels.

Second. An automatic hook which shall be positive and reliable in its action.

Third. One which shall speed up the handling of car wheels in the foundry.

Fourth. One which shall relieve the workmen of the exceedingly laborious and exhausting task of causing the attachment, by hand, between the jaws of the hook and the 20 inside surface of the wheel hub.

While this invention has been specially evolved for the purpose just mentioned, yet its use is not restricted thereto; in fact, it is possible that it may be adapted to a wide 25 variety of uses other than that specifically mentioned herein.

In the making of chilled cast iron car wheels, the wheels are removed from the molds as soon as the metal has cooled sufficiently for the wheels to hold their shapes.

30 At the time of removal from the molds, the wheels are still red hot, having a temperature of about 1900 degrees Fahr. In this condition they must be engaged by the hook and taken to the annealing pits, these pits usually accommodating a stack of 18 wheels vertically, which means that the pits have a depth of 16 feet or more.

35 Heretofore the practice has been for the workman to use iron rods of varying lengths, by means of which the mechanism of the hook could be tripped, thereby releasing the gripping members from engagement with the wheel. Obviously, this is a dangerous and 40 fatiguing task, especially when the wheels are taken out of the annealing pits. Here, the workman must stand on the edge of a pit from which the mass of red hot metal belches forth the breath of an inferno. With 45 one of the iron rods, the workman must reach

down into the pit, and as the jaws of the hook enter the wheel, he must trip the operating parts as best he may, whereupon an upward pull on the hook causes the grippers to engage the wheel, so that it may be lifted 55 up out of the pit. The hook is let down into the pit and pulled up therefrom, by any ordinary lifting device, such as the fall block of an ordinary traveling crane.

In using the present invention, the hook 60 may be caused to descend into the pit in the usual manner, but as soon as the grippers have entered the hole in the wheel to a predetermined depth, an automatic tripping mechanism comes into action, which causes 65 the grippers to engage the wheel.

The features of this invention, for which the protection of Letters Patent of the United States is desired, are collectively grouped in the claims concluding this specification.

70 In the drawings, which illustrate one embodiment of this invention,

Fig. 1 represents a side elevation showing the jaws in the retracted position ready to be tripped, in order to grip a wheel, the latter being shown in end elevation, part being broken away to show the hub in section;

Fig. 2, a section on line 2—2, Fig. 1;

Fig. 3, a section on line 3—3, Fig. 1, reflected from a mirror plane;

Fig. 4, a portion of Fig. 1, showing the principal parts in an alternate position;

Fig. 5, a view similar to Fig. 1, showing however, the alternate position of the parts, when the jaws have finally gripped the wheel;

Fig. 6, a vertical section through the structure defining a wheel pit;

Fig. 7, a plan, viewed from line 7—7 in Fig. 1, part being broken away for convenience;

Fig. 8, a bottom plan of a portion of Fig. 5; and

Fig. 9, an exploded perspective view showing the relation between several detailed 95 parts.

Referring to the drawings, the hook structure comprises two interacting bell-crank members A and B, having the long arms 10 and 12, and the short arms 14 and 16, 100

respectively. These members have a scissor action around the pivot member 15. The member A is journaled on the portion 17 of pivot pin 15 and bears against the collar 19, while the member B is tapped to engage the threaded portion 18 of pin 15. The member A is closely adjacent member B, but sufficient clearance is allowed so that member A shall swing freely. The nut 20 is tightened 10 against the lock washer 23, securely holding the desired adjustment between members A and B.

The pin 15 has the two pivot extensions 15-1 and 15-2 opposite each other, which 15 carry, respectively, the two shouldered protrusions 15-3, these latter being square in cross-section. On the shouldered protrusions are mounted the arms 21, these having correspondingly squared holes defined in their 20 bossed ends 21-1. Thus, the arms 21 are rigid relatively to the bell-crank member B.

At their opposite ends the arms 21 carry the pin 24 shouldered to form studs 24-1, on which are pivotally mounted the bell-crank 25 tumblers members 25, these latter carrying the pin 26 on which swings a yoke made up of the side members 27. Members 27 are rigidly mounted on the pin 23 by means of the clamping nuts 22. The studs are prefer- 30 ably squared at 24-2, so as to be held more firmly by arms 21. On the lower lobes of the bell-crank tumblers 25, are pivotally hung the stems 30, on whose lower ends may be adjustably threaded the pendulous contact 35 members 31, the latter being locked in any desired position, by the nuts 32.

The arm 10 carries the standard 34 which may be integral therewith, and at the top of 34 may be pivoted, by means of the pin 40 35, the arm 36. In a similar manner, the standard 38 is carried by the arm 12, and has pivoted at 39, the toggle arm 40, the two toggle arms 36 and 40 being pivoted together at 41. The bracket 42 of the stand- 45 ard 34, keeps the toggle arms from sagging, and the stool 43, which may be integral with the arm 12 and the standard 38, forms a stop for the pin 28, the tendency of the side members 27 being to swing the pin 28 to the 50 right, due to the eccentricity of the pivotal mounting between the side members 27 and the tumblers 25.

The ends of the scissor arms 10 and 12 are pivoted at 45 to the links 46 made of strap 55 iron and formed as shown in Fig. 7, producing the eyelet 47 through which passes the suspension ring 48, which latter may be engaged by the hook 49 forming part of the usual fall-block 50 (Fig. 6) of an ordinary 60 electric crane (not shown).

In the lower ends of the expandable short arms 14 and 16 of the bell-crank members A and B, are pivoted at 52 the outwardly serrated gripper jaws or grippers 53. These 55 grippers have the integral lugs 54, entered in

the slots 55 of the respective arms 14 and 16, and are engaged by the previously mentioned pivot pins 52. The grippers thus have a limited oscillating motion around their respective pivots, and are free to swing into such a position as will allow the serrated surfaces of the grippers to come into coincidence with any approximately vertical surface, such as that defined on the inside of a car wheel hub.

The automatic hook, as shown in Fig. 1, is in the closed position thereof, where the grippers 53 are in the retracted position. Here, the arms 14 and 16 are substantially in coincidence with each other, while the arms 10 and 12 are substantially in alignment with each other, being virtually locked in this relation by means of the toggle arms 36 and 40, which are in the straight line position. Consequently, it will be clear that as the automatic hook hangs in the crane hook 49, there will be an upward pull on the ends of the arms 10 and 12 which tends to compress the toggle arms. Now, when the automatic hook is lowered so that the grippers will enter the hole in the wheel hub, they will remain in the retracted or closed position until the lower faces of the contact members 31 touch the upper face of the wheel hub 61, as indicated in Figs. 1, 2 and 3.

As the automatic hook is lowered further, the contact members 31 push upwardly on the stems 30, and cause the tumblers 25 to move around their fulcrum 24, thereby moving the yoke members 27 upwardly. This causes the pin 28 to lift the toggle member 40, breaking the toggle straight line position, and immediately allowing the weight of the parts hanging on the links 46 to become effective to move the bell-crank members A and B about their common pivot 15. This expands the lower arms 14 and 16, pushes the grippers 53 outwardly until the inside or concave surface of the hub is securely engaged by the laterally rounded teeth of the grippers as indicated in Fig. 5. The heavier the weight to be lifted, the more securely will the same be now held by the grippers.

The positions of the movable parts indicated in Fig. 4, occurs at a point between the two extreme positions illustrated in Figs. 1 and 5, and visualizes the fact that after the toggle lock of Fig. 1 is broken, that sufficient time intervenes for the grippers to drop down into the hub of the wheel a considerable distance below the upper face thereof, so as to engage the hub in the manner shown in Fig. 5. The point at which the gripping mechanism is tripped, may be adjusted by screwing the contact members 31 up or down along the stems 30.

When it is desired to disengage the gripping members from the wheel, it is only necessary to lower the automatic hook until the wheel rests on the surface of a solid, as at 60, when a further lowering of the hook causes 130

the arms 10 and 12 (Fig. 5), to swing downwardly into the original aligned position indicated in Fig. 1, thus contracting the arms 14 and 16. Toggle arms 36 and 40 have meanwhile dropped back into the straight line position, locking the members A and B, so that the grippers are again held in the original retracted position. When the automatic hook is now lifted out of the wheel, the pendulous contact members 31 drop downwardly, pulling the tumblers 25 back into the position shown in Fig. 1.

In the ordinary hook which is in everyday use, bell-crank members similar to 10 and 12, and toggle locking members 36 and 40 together with lifting members corresponding to straps 46, are used. Therefore, we do not claim these members broadly, but only in combination with the automatic tripping or toggle-unlocking mechanism which has just been described. The pivoted gripping members 53 are novel, so far as we are aware.

The bell-crank members A and B, being mutually movable around a common axis, naturally have a scissor-like action, and so may be called "scissor members".

It is obvious, that in its broad aspect, the mechanism of the automatic hook herein described, is applicable to lifting devices adapted to operate on a variety of objects which may be gripped by advancing or retracting certain jaws members, these jaw members being carried by movable members that may be mutually expanded or contracted.

While a specific embodiment of this invention is herein shown and described, it must be clearly understood that all the detailed parts thereof are not necessarily in the preferred forms thereof. Hence, various modifications could be made without departing from the essential and characteristic features of the invention as defined by the spirit and scope of the claims.

Having fully described our invention, what we claim is:

1. An automatic hook comprising pivoted members having mutually expansible arms and corresponding operating-lever arms, standards on said lever arms, toggle arms connecting said standards, said toggle arms normally in alignment with each other to form locking members effective to hold said expansible arms in an initially contracted position, tripping members effective to push said toggle arms out of alignment, and contact members operably engaging said tripping members.

2. An automatic hook comprising scissor members having expansible gripper arms and lever arms for expanding said gripper arms, toggle arms normally in alignment with each other for locking said scissor members in a position where said gripper arms shall be contracted, and a tripping mechanism having contact members effective to move said

toggle members out of said alignment when said contact members are moved from an initial position thereof.

3. An automatic hook comprising bell-crank members pivoted to each other to have a scissor action, grippers actuated by said bell-crank members, toggle arms normally in alignment with each other for holding said bell-crank members in an initially locked position, a tumbler operable to trip said toggle arms, and pendulous contact members effective to actuate said tumbler.

4. An automatic hook comprising bell-crank members pivoted together to have a scissor action, suspension members effective to actuate said bell-crank members, standards on said bell-crank members, toggle members effective to hold said bell-crank members in an initially locked position, tripping members effective to move said toggle members from the said holding position, and contact members actuating said tripping members.

5. An automatic hook comprising bell-crank members pivoted to each other so as to produce expansive and contractive actions between corresponding arms of said bell-cranks, lifting members operably disposed to engage said bell-crank members, and grippers pivoted to the arms having said expansive and contractive actions, said grippers having laterally rounded teeth to engage concave surfaces.

6. An automatic hook comprising two bell-crank members, a pivot pin rigidly mounted in one of said members and oscillatingly mounted in the other member, arms rigidly mounted on said pivot pin, a fulcrum pin carried by said arms, a tumbler mounted on said fulcrum pin, toggle members effective to lock said bell-crank members in an initial position, a tripping yoke pivotally mounted in said tumbler in proximity to said toggle members, and contact members pivoted in said tumbler, said contact members being effective to cause the lifting of said tripping yoke under certain predetermined conditions.

7. A lifting device having in combination gripping members, bell-crank members actuating said gripping members, locking members holding said bell-crank members in an initially locked position wherein said gripping members are retracted, a tripping mechanism having a tripping member in proximity to said locking members, and pendulous contact member suspended from said tripping member.

8. A lifting device having gripping members, bell-crank members pivoted to each other to cause a scissor action effective to advance and retract said gripping members, arms spaced transversely apart from said bell-crank members, said arms being rigid to one of the said scissor members, a tripping mechanism supported by said arms and pivotally mounted in relation thereto, stools on

said bell-crank members, toggle members pivoted to said stools, said toggle members in the straight line position being in operable proximity to said tripping mechanism, and contact members effective to actuate said tripping mechanism under certain predetermined conditions.

9. A lifting device having in combination, gripping members, scissor members effective to actuate said gripping members, toggle members having substantially a straight line position effective to lock said scissor members, and a tripping mechanism effective to break the straight line position of said toggle members, and pendulous contact members suspended from said tripping mechanism.

10. A lifting device having in combination, gripping jaws, levers having mutually expansive and contractive motions effective to respectively advance or retract said gripping jaws, toggle members normally effective to hold said levers in a mutually contracted position, and a tripping mechanism having a pendulous contact member effective to break the normal position of said toggle members.

11. An automatic hook, including in combination, two bell-crank members having an arm of each substantially in alignment with an arm of the other when the hook is locked, a toggle spaced apart from and locking said aligned bell-crank arms, a tumbler pivotally supported between said bell-crank arms and toggle arms, a swinging yoke carried by said tumbler and disposed to engage said toggle, and a pendulous contact member suspended from said tumbler.

12. An automatic hook including in combination, two bell-crank members having an arm of each in operative conjunction with an arm of the other, toggle arms spaced apart from said bell-crank arms and extending in the same general direction to hold the bell-crank arms locked, a pivoted tumbler having means to engage a toggle arm, and a pendulous contact member suspended from said tumbler.

In testimony whereof, we sign our names hereto.

ANDREW HUSBERG.
GLEN L. GUTKE.
